UNITED STATES PATENT OFFICE.

EDWIN R. PROBERT, OF COVINGTON, KENTUCKY, ASSIGNOR TO THE MOESCHL-EDWARDS CORRUGATING COMPANY, OF COVINGTON, KENTUCKY, A CORPORATION OF KENTUCKY.

REFERENCE DEVICE FOR DESKS AND THE LIKE.

1,156,812.

Specification of Letters Patent. Patented Oct. 12, 1915.

Application filed February 7, 1913. Serial No. 746,769.

To all whom it may concern:

Be it known that I, EDWIN R. PROBERT, a citizen of the United States of America, and a resident of Covington, in the county of Kenton and State of Kentucky, have invented a certain new and useful Improvement in Reference Devices for Desks and the like, of which the following is a specification.

This invention relates to ready-reference devices for use in presenting convenient information to the occupant of a desk or the like, and the invention consists of a series of metallic plates, each of which is adapted on one or both of its faces to the attachment of sheets containing information and figures relating to materials, prices and the like, and an indexed or indicator tab or handle projecting forwardly from the outer end of each metallic plate; and the invention further consists of a vertical series of horizontal plates of metal or other suitable material, paper or like sheets having classified information produced thereon and stuck or otherwise suitably attached to one or both faces of each of said plates, indexed tabs or handles projecting forwardly from the outer ends of said plates and having printed or written matter thereon that conforms to the information on the respective sheets, and guide-ways adapted for the sliding and supporting engagement of the opposite longitudinal edges or sides of said plates; and the invention still further consists of a vertical series of horizontal plates of metal or other suitable material adapted to receive duly attached paper sheets of classified information on one or both faces of each plate, reinforcing hems made along the opposite longitudinal edges or sides of each plate, indexed tabs or handles projecting from the outer ends of the respective plates, a drawer-front having short slots or elongated openings made therein and adapted to freely accommodate the said indexed tabs or handles of each of said plates so that the outer ends of said indexed-tabs project a suitable viewing and manipulating distance from the face of said drawer-front and so that each plate can be drawn outwardly with said drawer-front independent of the other plates, and crimped sheets or strips of metal forming guide-ways adapted to the sliding and supporting engagement of the opposite longitudinal edges or sides of said plates.

Other features of the invention herein will be fully hereinafter described and particularly pointed out in the claim.

In the accompanying sheet of drawings, Figure 1 is a fragmentary perspective view of one upper end of an ordinary flat-top desk showing my device in closed position and occupying the place of the ordinary upper drawer of the desk, which is the most convenient position for the occupant in connection with the special use of the invention referred to herein; Fig. 2, a fragmentary cross-section showing the top-drawer pocket or chamber having a vertical series of horizontal guide-ways at both sides of said chamber; Fig. 3, a fragmentary elevation, partly in section, showing the top drawer-front and one of its two inwardly-extending longitudinal bars that engage guide-ways or pockets that lie parallel to but beneath the vertical series of horizontal guide-ways for the sliding-plates referred to in connection with Fig. 2; Fig. 4, a detail perspective view of one of the special forms of crimped sheets or strips of metal that are adapted to form the vertical series of horizontal guide-ways at both sides of the top-drawer chamber; Fig. 5, a detail perspective view showing one of the metal plates having a forwardly-projecting indexed tab or handle at its outer end and adapted to be slid along the guide-ways seen in Fig. 4; and Fig. 6, a detail perspective view showing fragments of the drawer-front, crimped guide-way sheet or strip and indexed-tab sliding-plates that engage said guide-ways.

1 indicates the flat top of a desk; 2 the vertical side-wall to the left; 3 the inner-wall of the chamber or casing adapted to contain the usual vertical series of drawers; and 4 the back-wall of the desk.

5 indicates the customary second drawer of the desk that lies beneath the top drawer with an intervening horizontal partition 6, as customary.

Instead of using an entire drawer in the top-chamber of the drawer-casing I use what may be termed a skeleton drawer that is without sides, rear end or bottom, a front 7 of the usual form having lower, longitudinal side bars or rear extensions 8 that are dovetailed at 9. An ordinary handle 10 is attached in place to the drawer-front 7, preferably near its central lower edge, as

best seen in Figs. 1 and 3. This handle 10 is the usual manipulating one and is used for facilitating the drawing of the skeleton drawer outwardly from its pocket in the upper part of the drawer-casing.

11 indicates each one of a vertical series of horizontal grooves or guide-ways provided in the opposite sides of the top-chamber of the drawer-casing and preferably formed in a sheet or strip of crimped sheet-metal, as best seen in Fig. 4, such crimped sheet being readily made and just as readily attached in place by means of tacks 12 driven into the sides 2 and 3, as best seen in Fig. 2. Of course strips of wood or the like can be provided instead of sheet-metal strips and suitable guide-ways made in the inner faces thereof for the purpose that I shall presently describe. The wooden strips, however, would not be as convenient or stand the wear of the sheet-metal ones and not as readily made.

13 indicates an upturned right-angled flange made along the lower edge of each of the sheets or strips that contain the guide-ways 11. These flanges 13 form guide-ways for the lower rear extensions or bars 8 of the skeleton drawer and, also, form supports for said bars 8 that, in turn, form supports for the drawer-front 7.

14 indicates each one of a vertical series of plates made of sheet metal or other suitable material adapted to engage along their longitudinal sides or edges with the grooves or guide-ways 11, suitable tabs or tongues 15 projecting forwardly from the outer or fore edges of the plates, as best seen in Figs. 1 and 5. These tabs or tongues 15 form means by which the plates 14 are drawn along the guide-ways 11 from within the upper chamber of the drawer-casing and are adapted to contain index-matter of any kind to show or indicate what each of the plates 14 has in the shape of classified, tabulated, or other information of any kind on one or both of its faces. The said tabs or tongues 15 extend forwardly through slots 16 that are made in the drawer-front 7 out of horizontal alignment or in a gradually descending line, the said tab on the lowermost plate being nearest its right-hand edge while those on the succeeding plates above gradually ascend to the left-end of the drawer-front. The said slots 16 taper inwardly so that they are widest on the inner face of the drawer-front 7, as best seen in Fig. 3 and so that the tabs or tongues 15 of all the plates 14 can more readily engage said slots as the drawer-front 7 is being slid into closed position in the desk.

It is not absolutely requisite to have the drawer-front 7 in the opening leading to the chamber in which the reference-carrying plates 14 are housed, except to protect the matter contained on said plates from un-

authorized use and dust, or other injurious exposure, a suitable lock being provided in said drawer-front 7 for fastening it in closed position and preventing access to said reference-carrying plates by unauthorized persons. It is not absolutely necessary either to have the slots 16 made in said drawer-front 7, as the plates can be made shorter so that the tabs or tongues 15 will not project forward beyond the inner face of said drawer-front 7 when closed. In such event the drawer-front 7 can be readily drawn outward and access easily had to the several tabs or tongues of the plates within. In such event, too, there is no danger of tearing or injuring contact of the clothes and person with the projecting tabs.

In order to operate the device as it is shown in Fig. 1 of the drawings, with the slots 16 in the drawer-front and the tabs or tongues 15 extending outwardly, it is only necessary to take hold of one of the tabs or tongues 15 that contains the information desired and drawing outwardly, which act draws the skeleton drawer with that particular tab or tongue independent of the other plates within the upper chamber of the desk and without disturbing any of the other plates. If either of the other plates is wanted forward the one already extended forward can be slid into closed position without closing the skeleton drawer and then said other desired one can be drawn outward. The skeleton drawer can remain open or drawn out altogether if desired, if ready or unobstructed access to the plates within is desired. The handle 10 of the drawer-front 7 can be used as customary for facilitating the sliding-movement of said drawer-front 7 to and from closed position.

The plates 14 are adapted to the attachment by sticking or otherwise to one or both of their respective faces, of sheets of paper or the like containing printed matter in the shape of tables of figures, market quotations, current prices, weights and measures, timetables, telephone lists, and, in fact, information of all kinds for handy-reference by the occupant of the desk in making up estimates or bids or compilations of all kinds. Fig. 5 shows how strips of printed sheets 17 or otherwise prepared sheets or clippings from catalogues or newspapers, or leaflets, containing quotations or other desired matter, can be attached to the face of the plate for immediate reference and out of the way of other matter on the desk and occupying a place in the desk, practically "all its own," and readily replaced by other quotations, prices and the like to suit the conditions of the current or passing markets.

To somewhat stiffen the skeleton drawer so that the side-bars 8 will not have any lateral movement or become loose from the drawer-front 7, I provide braces 18 that

clear the upper edge of the flange 13 in the space 19 above said flange in the sliding movements of said skeleton drawer.

To somewhat stiffen the opposite longitudinal edges of the plates 14, so that lighter material might be used, I provide hems 20, as best seen in Fig. 5.

I claim:—

A ready-reference file device comprising a vertical series of horizontal plates of metal or other suitable material adapted to receive duly-attached paper sheets of classified information on one or both faces of each plate, reinforcing hems made along the opposite longitudinal edges or sides of each plate, indexed tabs or handles projecting from the outer ends of the respective plates, a drawer-

front having short slots or elongated openings made therein and adapted to freely accommodate the said indexed tabs or handles of each of said plates so that the outer ends of said indexed tabs can project a suitable viewing and manipulating distance from the face of said drawer-front and so that each plate can be drawn outwardly with said drawer-front independent of the other plates, and crimped sheets or strips of metal forming guide-ways adapted to the sliding and supporting engagement of the opposite longitudinal edges or sides of said plates.

EDWIN R. PROBERT.
